UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

PARTITION JUNCTION-BOX.

1,191,327.

Specification of Letters Patent

Patented July 18, 1916.

Application filed July 15, 1914. Serial No. 251,160.

To all whom it may concern:

Be it known that I, JAMES F. McELROY, a citizen of the United States, residing at Albany, county of Albany, State of New York, have invented certain new and useful Improvements in Partition Junction-Boxes, the following being a full, clear, and exact disclosure of the one form of my invention which I at present deem preferable.

For a detailed description of the present form of my invention, reference may be had to the following specification and to the accompanying drawings, which illustrate my invention, wherein—

Figure 1 is a horizontal section of my device, looking down upon the switch lever; Fig. 2 is a plan of the switch-portion of the device; Fig. 3 is a side elevation of the internal parts with the casing in section; Figs. 4 and 5 show the switch-lever and the bearing-base therefor detached.

My invention relates to a junction-box and, in particular, one designed to be set in a partition wall, and serve as a combined junction-box and switch.

Referring to the drawings, F represents the casing of my device. It includes two portions, one on each side of a partition-wall E, to which it is secured by means of flanges f, f projecting outwardly from the exterior of the casing at a point about midway between its two sides. The casing is of a depth greater than the thickness of the partition wall.

The portion of the box which is exposed on the right-hand side of wall E, as it appears in Fig. 3, and projects therefrom, is the junction-portion thereof. It is provided with a removable cover F¹ and also with an opening in an extension at the bottom, for the entry of the line-wire tube G. This extension is made as a part of the removable cover F¹, so that the casing can be inserted in the partition from the left-hand side

thereof without any more cutting of the partition than is required to give an opening fitting closely around the rectangular portion of the box. Then when it has been so inserted in the partition, and the tube G

also placed in position, the removable cover F¹ can be applied from the right-hand side of the partition to not only close the box, but to also cover over and include the tube G, in the interior of the casing. When the cover F¹ is attached to the casing and to the wall E, by screws or other similar de-

vices, as shown, it aids in securing the casing to the partition.

The part which is exposed on the left-hand side of the partition E and projects therefrom is the switch-portion of the casing, being provided on its under side with a wide slot or opening in which the switch-operating handle can travel both laterally and forward, and containing the switch contacts, lever and bearing-base of the switch. Within the casing is fixed a plate of insulation D which, as shown in the drawing, divides the interior of the casing into two compartments. On the junction-box side the said plate D carries the junction-terminals to which may be secured the wires entering the casing through the tube G in a manner well understood in the art. On the switch side of the casing the said plate D carries a bearing-base of the form shown in detail in Fig. 5. Said base comprises a flat plate-portion C secured against plate D, and a ring or ring-portion C¹ projecting therefrom at right angles to the part C. The circular opening of the ring-portion C¹ is indicated by the letter c. The crest of the ring C¹ is provided with two projecting lugs c¹, c² forming between them an open-ended slot, while a similar slot, but not open-ended, is cut in the end of flat plate-portion C directly below the slot between c¹ and c². At the opposite extremity of the said flat portion C are two slight projections forming between them a notch a, and just in front of the notch a is a stud c³ for attaching a spring, as will be hereinafter explained.

The movable switch-member is shown in detail in Fig. 4 and includes a shank A, to one end of which is secured the insulating knob A¹. On the opposite end of shank A is a disk B, extending at right angles to the shank A, and provided on its outer side with two lugs b, b. The shank A also carries a downward projection A² adapted to enter and fit into the aforesaid notch a on the flat base-piece C. These two parts, which may be made as castings, to-wit, the bearing-base and the movable member or lever, comprise the fundamental parts of my switch. They are assembled, as shown in Figs. 1, 2 and 3, by passing the knob A¹ and shank A through the ring C¹, until the disk B bears against the outer face of the ring. A pin K is then passed downward through the slot between lugs c¹, c², into and through the lugs b, b, on disk B, and into

the slot in the end of the flat base-piece C. This pin is secured to lugs b, b by a small fastening pin. Then a tension spring S is secured at one end to the stud c³ and at the other end to the aforesaid pin K at a point between the lugs b, b. The spring draws the disk B down to its normal flat bearing against the outer face of ring C¹, thereby holding the switch-lever control, as shown in Fig. 2, and also drawing its lower end inward toward base plate C, so that the projection A² of the lever will engage the notch a and be locked thereby in its said central position.

To move the switch lever to either side, away from its central position shown in Fig. 2, it is necessary to first draw it slightly forward to bring the projection A² out of notch a. In this movement the lever fulcrums around the inner edge of disk B nearest to the base-plate C. The lever may then be moved sidewise against either one of the contact-springs appearing on either side of the shank A in Fig. 2. In this side movement, the lever will fulcrum on one of the lateral edges of the disk B. All of the lever movements will obviously be resisted by the spring S, which tends to hold disk B flat against the outer face of ring C¹. Hence when the lever has been moved to one side or the other, to close the circuit by engaging one of the contact springs on either side of it, the spring S will return the lever to its central position, as soon as it (the lever) is released, and will also lock it in that position by drawing projection A² into notch a.

The construction thus described is extremely simple and cheap, considering the duties that it performs, and I have found it of value in situations, such as a railway car, where the motorman in his cab on one side of partition E desires to close momentarily either a car-door-opening circuit, or a car-door-closing circuit as the case may be. The line-wire tube G will rise on the opposite side of partition E.

What I claim as new and desire to secure by Letters Patent is:

50. 1. A partition junction box comprising a section having means for engaging a partition wall and located to cause a portion thereof to project through said wall when engaged therewith, a removable cover attached to the portion to be projected through the wall, and provided with means to aid in securing said section in position, and means within said section for supporting terminal connections on the cover side of said wall and switch contacts on the other side of the wall.
55. 2. A partition junction box comprising a section having means for engaging a parti-

tion wall and located to cause a portion thereof to project through said wall when engaged therewith, said section having a wide opening in one end, a removable cover attached to the portion to be projected through the wall, and provided with means to aid in securing said section in position, and means within said section for supporting terminal connections on the cover side of said wall and switch contacts on the other side of the wall.

3. A partition junction box comprising a section having means for engaging a partition wall and located to cause a portion thereof to project through said wall when engaged therewith, a removable cover attached to the portion to be projected through the wall, said cover having means for embracing a line wire tube, and means within said section for supporting terminal connections on the cover side of said wall and switch contacts on the other side of the wall.

4. A partition junction box comprising a section having means for engaging a partition wall and located to cause a portion thereof to project through said wall when engaged therewith, a removable cover attached to the portion to be projected through the wall, said cover having an extension for clamping a line wire tube against said wall, and means within said section for supporting terminal connections on the cover side of said wall and switch contacts on the other side of the wall.

5. A partition junction box comprising a section having means for engaging a partition wall and located to cause a portion thereof to project through said wall when engaged therewith, said section having a wide opening in one end, a removable cover attached to the portion to be projected through the wall, said cover having means for embracing a line wire tube, and means within said section for supporting the terminal connection on the cover side of said wall, and switch contacts on the other side of said wall.

6. A partition junction box comprising a section having means for engaging a partition wall and located to cause a portion thereof to project through said wall when engaged therewith, said section having a wide opening in one end, a removable cover attached to the portion to be projected through the wall, said cover having means for embracing a line wire tube.

In witness whereof I have hereunto set my hand, before two subscribing witnesses, this 6th day of July, 1914.

JAMES F. McELROY.
